UNITED STATES PATENT OFFICE.

REAMEY H. DYER, OF ROANOKE, VIRGINIA.

JOURNAL-BOX-WASTE RETAINER.

Application filed July 28, 1926. Serial No. 125,363.

This invention relates to the lubrication of journal boxes, especially railway car journal boxes and, more specifically stated, consists in an improved device for holding down and keeping in place the oil-soaked packing commonly used to lubricate such axle journals. Such devices are known as "waste retainers" and various forms have heretofore been used or proposed, but without practical success, as far as my experience goes.

As is well known, the oil-soaked waste is packed in the bottom of the journal box so that it is in contact with the lower half of the axle journal, to which it supplies the lubricant or oil, which is carried around on the journal between the latter and the bearing or brass resting on the upper half of the journal.

In use, this packing, instead of remaining in the bottom of the box, tends to creep up on the side of the journal opposite to the direction of movement of the vehicle, so that, in time, most of the packing will accumulate on that side, with the result that the oil drains into the bottom of the box, leaving the packing almost dry. Insufficient oil is then transmitted to the journal and its brass, and the bearing becomes unduly heated, resulting in a "hot box".

Furthermore, the collar on the end of the journal acts to cause some of the packing to be forced up around the end of the journal into the front portion of the box; also the waste gets between the journal and the brass when the latter lifts, as it does when a sudden stop is made, causing what are known as "waste grabs", all of which injuriously affects the efficient operation of the bearing.

Another prolific cause of losses to railroads is the stealing of the oil-soaked waste from the boxes, which is of frequent occurrence in some localities, the waste being taken, for example, for lighting fires, by simply lifting the lid of the box and pulling out some of the waste.

All these defects, incident to journal boxes as now used, are obviated by my improved waste retainer, which is illustrated in the accompanying drawing, in which,

Fig. 1 is a longitudinal vertical section of a car journal box, showing the axle journal and my improved waste retainer in side elevation.

Fig. 2 is an end view, partially in section, taken on line 2-2 of Fig. 1, and

Fig. 3 is a plan view of one embodiment

of the retainer constituting my present invention.

All waste retainers heretofore proposed, as far as I am aware, either comprise some form of springs or else are made of wire. I have found that the pressures exerted are so great that spring devices will not last and have therefore devised the present form in which the retainer is an integral rigid pressed-steel structure, requiring no springs or other adjuncts to maintain it in operative position. My retainer possesses additional advantages over retainers heretofore patented or proposed, as will appear herein after.

As seen in Fig. 3, the retainer is generally of U-shape, comprising a relatively wide transverse front end 1 and two relatively narrow legs or side members 2. The end 1 and the legs 2 are downwardly flanged at their outer edges, the front flange being shown at 3 and the side flanges at 4, said flanges serving to prevent the waste from working up around the edges between the retainer and the walls of the box; the side members 2 are reduced in width near their middle, as shown at 5, and their rear ends 6 are of less width than their front portions, to enable the retainer to be inserted in the box when in place on the journal. The flanges 4 are also cut away, as at 7, in the middle portion of the legs, and are of less depth on the rear portions 6 than in the front portions. The tops of the legs adjacent the front end 1 are cut out, as at 9, to accommodate the collar 10 on the end of the journal 11. The retainer shown is for use in pressed steel boxes, which comprise internal projections 24, through which journal box bolts 25 are passed, see dotted lines in Fig. 3, which is why the side members or legs of the retainer are cut away in the middle and reduced in width in their rear portions, so that the retainer can be inserted in the box around the journal by 100 tilting it somewhat. Cast-iron boxes, however, do not have said projections and bolts, so that retainers for use in them, need not have their legs so reduced but they may be of uniform width throughout. The essential 105 feature of either form of retainer is now to be described.

From the inside edges of the side legs extend upwardly the integral checks 12, which are bent over at their top edge to form the horizontal bearing faces 13 which, as shown, are of semi-circular contour in their front

portions with narrow parallel sided extensions 14 running rearwardly therefrom. The reduction in width, and depth of flange, of the legs is as above stated, to enable the retainer to be applied to any of the types of box in common use, including the pressed steel box, it being only essential that the retainer should fit snugly, without binding and with a little play, between the journal and the sides of the box, to prevent the waste from working up between the retainer and the sides and end of the box, as well as between the retainer and the journal and to make it impossible for the waste to be removed from the box without jacking it up.

In Figs. 1 and 2, the invention is shown applied to a cast-iron journal box, comprising a bottom wall 15, a front wall 16, a hinged cover 17, side walls 8 and a rear wall 18, through which latter the journal 11 of the axle 19 is passed. The bearing brass 20 fits on the journal and a wedge 21 fits between said brass and the top 22 of the box, as usual.

The oil-soaked packing or waste 23 is placed in the bottom of the box in sufficient amount so that when the retainer is inserted with its legs on each side of the journal, its top surface lies approximately in, or slightly below, the horizontal plane containing the axis of the journal, and the top surfaces 13, 14 of the cheeks 12 contact with the bottom surfaces of the brass 20. The retainer is thus positively held down in place on the waste by said brass and cannot become displaced while it is free to follow the movements of the same relatively to the box. The pressure of the retainer on the waste at the sides of the journal forces the waste under the journal upward, against the same. The retainer being a solid, rigid, integral structure, and no springs or spring material being used, there is no possibility of its getting out of proper position or of any part being broken. As is well known, durability and simplicity,—in short, ruggedness,—are essential characteristics of devices used on the rolling stock of railways, and my invention embodies such characteristics to the fullest extent possible.

Having thus described my invention, what

50 I claim is:

1. A floating waste retainer for car axle journal boxes, consisting of an integral metal structure, comprising a transverse end member and side members extending rearwardly

from the said end member so as to lie on each side of the axle journal, the outer edges of said side members being shaped in accordance with the box walls to enable the retainer to be inserted and removed without difficulty, said side members having vertical portions extending upwardly from their inner edges throughout a portion of their length, and said vertical portions being bent back at their tops to form horizontal portions extending outwardly and adapted to contact the bottom surfaces of the bearing brass fitted on the journal.

2. A waste retainer for car axle journal boxes, comprising a front member, side members extending rearwardly therefrom, said members having downwardly projecting flanges at their outer edges, and cheeks extending upwardly from the inner edges of said side members and having horizontal bearing faces at their tops, as and for the purpose described.

3. Floating means to hold the packing in place in car journal boxes, comprising a one-piece metallic structure having parts adapted to lie on each side of the journal and substantially cover the space between the latter and the sides of the box, a part adapted to lie across the end of the journal and substantially cover the space between said end and the lid of the box, downwardly extending flanges on the edges of said parts, and an upward extension on each of said first mentioned side parts adapted to come into contact with the under side of the journal brass to thereby hold the packing in place and prevent its unauthorized withdrawal.

4. A device for use in car axle journal boxes to maintain the oil-soaked waste in position, to press it up against the lower side of the journal and to prevent its being stolen, comprising a U-shaped metal structure with downwardly projecting flanges on its edges, the end member adapted to fit between the end of the journal and the lid of the box and the side members adapted to fit between the sides of the journal and the side walls of the box, and upward extensions on the side members adapted to be engaged by and be pressed down by the journal brass.

In testimony whereof I have hereunto set my hand.

REAMEY H. DYER.
